UNITED STATES PATENT OFFICE.

HENRY HOFFMANN, OF ST. LOUIS, MISSOURI.

SHELVING.

No. 908,772.

Specification of Letters Patent. Patented Jan. 5, 1909.

Application filed June 18, 1908. Serial No. 439,116.

To all whom it may concern:

Be it known that I, HENRY HOFFMANN, a citizen of the United States, residing at St. Louis, Missouri, have invented certain new and useful Improvements in Shelving, of which the following is a clear, full, and exact description.

My invention relates to shelving, and its object is to simplify and cheapen the construction of the same, and also to make the different parts thereof detachable and to increase the capacity of the same as may be required.

It is also my object to provide an arrangement whereby shelves of many different styles and adapted to hold various articles of merchandise may be supported. For example, with my improvement shelves such as plain boards for unbreakable articles or trays with a back, two sides and an open front for breakable articles or flat trays with low projecting guards around the edge for miscellaneous articles, may all be interchangeably supported on my shelving construction.

In the embodiment of my invention shown in the drawings I have only shown one preferred form of tray, which is constructed like an open top box having the front side detachable, but it is obvious that other forms of trays may also be used as desired without departing from the spirit or scope of my invention.

My invention will be defined in the claim.

In the drawings, Figure 1 is a perspective view of the entire frame; Fig. 2 is a section 35 through the front standards of said frame and with a portion of the front wall of the trays broken away; and Fig. 3 is a perspective view of one end portion of a shelf hanger.

My shelf frame preferably consists of a series of upright standards 1, said standards having formed therein several groups of apertures 4 at different heights, the apertures of each group being of the same height for supporting oppositely arranged shelf hangers. Each pair of standards is adapted to support a shelf hanger which is constructed as shown, and is composed of a longitudinal angle bar 2 having projecting bosses 3 near the adjacent ends of the same for insertion 50 in the apertures of said standards. The

bosses 3 are provided with means to retain them in said apertures, and in the present embodiment I have shown said bosses formed into an ogee-shaped curve for this purpose. By this construction it is obvious that when 55 these bosses 3 are inserted in the apertures 4 of the tubular standards, the ogee-shaped curve retains them therein. At the rear end of each angle bar is a turned-up portion 7 shown in Fig. 3, which forms a back stop for 60 the trays as they are pushed in upon the hangers. The tray consists of an ordinary receptacle having an open top for the purpose of receiving bottles or other similar articles of breakable nature used in tray quantities. The front of each tray is made removable and for this purpose has at one end an ordinary bolt, and at the bottom and other end projecting dowels to fit in sockets prepared for the same in the bottom and side of 65 the receptacle. 70

My shelf frame is assembled as follows. An angle bar is first attached to pairs of oppositely facing standards. In order to attach the angle bar to said standards it is 75 obvious that the angle bar thereof is held upwardly until the ogee portion has been inserted in the aperture of the standards, and then the angle portion is permitted to drop and rest against the sides of the standards, the ogee portions retaining them thereon. When several angle bars have thus been attached to the standards, the trays or shelves are pushed in to rest upon the horizontal portions of oppositely arranged angle 80 bars to bring up against the rear back stop 85 7 of each angle bar. It is obvious that the capacity of my frame may be easily increased by adding more angle bars and shelves. 90

What I claim is:

In a shelving construction in combination, a series of vertical standards having groups of apertures therein, at different heights the apertures of each group being of 95 the same height, pairs of oppositely arranged shelf hangers mounted on said standards at equal heights, each hanger composed of longitudinal angle bars having a horizontal portion for supporting shelves, and a vertical 100

portion throughout its entire length provided with vertically projecting ogee shaped rods adapted to be inserted in the apertures of said supporting standards and retained 5 therein for supporting said hangers, and a series of shelves adapted to rest upon the horizontal portions of said shelf hangers, one end of said horizontal portions of each

of said hangers being turned up vertically to form a back stop for said shelves.

Signed at the city of St. Louis, Mo., this 15th day of June, 1908.

HENRY HOFFMANN.
